CHAIN CONVEYER

Curt G. Joa, Sheboygan Falls, Wis.

Application January 16, 1947, Serial No. 722,329

11 Claims. (Cl. 198—189)

1

This invention relates to a conveyor system, and more particularly to an improved continuous chain conveyor for use therein.

Conveyor systems employing pivotally connected chain links as the conveyor means proper are widely used in carrying wood and like work pieces into engagement with a tool, as a saw, shaper, planer or the like. The conventional type conveyor has a smooth upper surface with certain of the links in the chain being provided with upstanding work impelling lugs which engage the trailing edge of the work piece. Such lugs not only prevent slippage of the member being carried on the conveyor but also provide a seat against which the work piece may be squared before it reaches the tool. In many cases, however, it is not feasible to employ such lugs, and the problem then becomes one of increasing the friction between the top surface of the conveyor and the work piece. Such increased friction is commonly afforded by corrugating or otherwise roughening the top surface of the feed chain, but this practice is one which has several disadvantages. The roughened surface often mars the under surface of the work piece; further, when lugs are again mounted on a chain of this type, the roughened surface thereon tends to prevent the work pieces from seating squarely against the lugs.

It is therefore a primary object of the present invention to provide a conveyor of the chain type which may advantageously be employed either with or without work impelling lugs and which, with lugs removed, provides a surface that affords good frictional engagement with a work piece but will not mar the same in any manner, and which, with lugs attached, presents the conventional smooth surface to any work piece carried on the conveyor.

Other objects of the present invention will become apparent from a consideration of the following description and appended claims, and of the drawing, wherein:

Fig. 1 is a view in side elevation of a portion of a chain type conveyor embodying the features of the present invention, a support for the conveyor being also shown.

Fig. 2 is a view in perspective, on an enlarged scale, of one of the links employed in said conveyor and of a lug arranged to be mounted on said link.

Referring more in detail to the drawing:

Generally indicated at 10 is a portion of a conveyor chain made up of pivotally connected links 11 and 12. The links 11 have side plates 13 which

2

extend at both ends of the link beyond an intervening block 14 to provide ears 15. The ears 15 are apertured at 16 to receive pintles 17. Links 12 comprise blocks 18, and each of these blocks is provided at its ends with an extension 19 which fits between the ears 15 on links 11. The extensions 19 are provided with transverse openings to receive pintles 17 whereby links 11 and 12 are pivotally connected. It will be understood that 10 the two different types of links are used in alternation throughout the link of the chain.

The links 11 and 12 are here shown as provided with lower bearing surfaces 20 which engage against complementary, trough-shaped bearing surfaces 21 formed in the top of the conveyor support 22, but the provision of such complementary bearing surfaces forms no part of the present invention, links of this character being more particularly described in my Patent #2,304,571, 20 issued December 8, 1942.

Certain of the links 11 along the chain are modified to receive work impelling lugs 23 which are secured to the links by means of screws 24, the screws engaging registering apertures 25 in 25 the lugs and in the blocks 14. Each lug is undercut to provide a transverse slot 26, and each lug is also provided with a depending transverse tongue 27 which fits within a complementary groove 28 formed in the side plates 13 and the block 14 when the lug is seated on the link. Secured to the block 14 between the groove 28 and the aperture 25 is a projecting rubber pad element 29 here shown as seated within a pocket 30 in the block.

35 When the conveyor chain 10 is used without its lugs, the projecting rubber pads 29 engage the lower surface of the work pieces carried on the conveyor, and the requisite increase in friction 40 between the conveyor and the work piece is thereby provided. Obviously, the work pieces can in no way be marred as a result of their contact with the rubber pads 29. Other resilient or non-rigid materials than rubber can be employed with 45 success in practising the present invention provided that such other materials have a sufficiently high co-efficient of friction. However I prefer to employ rubber for this purpose.

When the lugs 23 are again emplaced on the 50 chain and secured thereto, they effectively cover the pads, the latter fitting within the slots 26 formed in the undersurface of the lugs. Once covered in this fashion, the pads 29 cannot interfere with the proper seating against the lugs of 55 the work pieces carried on the conveyor.

I claim:

1. In a conveyor, the combination of pivotally connected links, with projecting friction increasing means mounted on the outer, work engaging surface of said links, and with lugs in detachable engagement with said links, said lugs in the engaged position substantially covering the friction increasing means.

2. The combination of claim 1, wherein said friction increasing means comprises a rubber block.

3. The combination of claim 1 wherein said friction increasing means comprises a rubber block having a substantially flat top surface positioned for engagement with the under surface of a work piece carried on the conveyor, and wherein said lugs are provided with a slot arranged to receive said rubber blocks on engagement of said lugs with the chain, whereby said blocks are covered.

4. The combination with a conveyor chain link having an outwardly projecting work engaging pad, of a detachable lug having a recess in which said pad is disposed, said lug and link having mechanically interlocked thrust transmitting parts.

5. The combination with a conveyor chain link having a work-engaging pad, of a detachable lug having a recess in which said pad is disposed, said lug and link having mechanically interlocked thrust transmitting parts, together with a bolt in threaded connection with the link and passing through the lug for detachably holding the lug to the link.

6. A conveyor in combination with a chain comprising links certain of which are provided with work engaging pads, of lugs detachably connected with the links provided with such pads and adapted to provide positive propulsion in lieu of frictional propulsion for work carried by the conveyor, each such lug being detachably bolted to a respective link immediately adjacent the pad carried thereby.

7. The combination set forth in claim 6 in which each lug comprises a cover for the pad on the link on which the lug is mounted.

8. The combination set forth in claim 6 in which each link upon which a pad is mounted is notched and each lug comprises a cover for the pad of such link and has a thrust block engaged in the notch of the link.

9. In a conveyor, a link comprising a central block and longitudinally projecting laterally spaced ears, said block being transversely kerfed and provided with an intermediate recess and a threaded aperture beyond the recess, and a pad seated in the recess.

10. The combination set forth in claim 9 in further combination with a plate having a rib engageable in the kerf of said block and having a recess complementary to that of the link and in which said pad is received, said plate being provided with a socket over the threaded aperture of the link and with a work propelling lug, together with a bolt extending through the socket and engaged in the aperture and comprising means detachably securing the plate and lug to the link.

11. A conveyor chain incorporating links provided with projecting friction pads, said pads being arranged for engagement with the lower surface of a workpiece carried on the chain, and lug means detachably mounted on the chain in a position to cover said friction pads.
